CLAIM

The ornamental design for a cake server set, as shown and described.

DESCRIPTION

FIG. 1 is a front perspective view of a cake server set, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is an enlarged view of detail “8” shown in FIG. 2; and,

FIG. 9 is an enlarged view of detail “9” shown in FIG. 2. The short dash-long dash broken lines encircling portions in FIG. 2 and illustrated in enlarged views in FIGS. 8 and 9 form no part of the claimed design.
